[57] CLAIM

The ornamental design for a modular seat, as shown and described.

DESCRIPTION

FIG. 1 is a view in perspective of a modular seat embodying the new design;

FIG. 2 is a front elevational view of the modular seat shown in FIG. 1;

FIG. 3 is a top plan view of the modular seat shown in FIG. 1;

FIG. 4 is a side view of the modular seat shown in FIG. 1; FIG. 5 is a rear elevational view of the modular seat shown in FIG. 1;

FIG. 6 is a view in perspective of an alternate modular seat embodying the new design;

FIG. 7 is a front elevational view of the modular seat shown in FIG. 6;

FIG. 8 is a top plan view of the modular seat shown in FIG. 6;

FIG. 9 is a side view of the modular seat shown in FIG. 6; and,

FIG. 10 is a rear elevational view of the modular seat shown in FIG. 6.

The broken lines represent environmental structure and form no part of the claimed design.
